ATTORNEY.

UNITED STATES PATENT OFFICE.

ERNST ORTWIG, OF COLOGNE-EHRENFIELD, GERMANY.

TOOL-HOLDER.

1,387,862.

Specification of Letters Patent. Patented Aug. 16, 1921.

Application filed August 15, 1919. Serial No. 317,724.

To all whom it may concern:

Be it known that I, ERNST ORTWIG, a citizen of the German Republic, and residing at Cologne-Ehrenfeld, Germany, have invented certain new and useful Improvements in Tool-Holders, of which the following is a specification.

The present invention has reference to certain new and useful improvements in tool holders, and relates more particularly to a universal or multiple tool holder to be used in connection with lathes, planing, shaping or the like machines, and the attachment essentially comprises a supporting member and a revoluble head thereon having a plurality of tool clamps in which a corresponding number of tools are mounted, any one of which may readily be brought into operative position relative to the work piece by releasing a latch bolt which normally relatively locks the tool holding head, rotating the latter until the required tool is opposite the work, and then locking the head again. Each tool is secured to the revolver head by a stirrup-shaped clamping member, which clamps in turn are adjustably secured in elongated seat slots in the revolver head.

In order to make my invention more readily understood, I will now describe it in detail with reference to the accompanying drawing, in which Figure 1 is a side elevation of the tool holder, sectioned on line A—B of Fig. 2, which latter figure is a front view of the device; Fig. 3 represents a top view.

The supporting member 1, which is designed to be secured to the tool rest of the machine, terminates in a somewhat laterally disposed tubular bearing socket 2 with conically tapering inner wall. The tool holding revolver head 3 is rigidly concentrically secured to a conical journal bolt 4 fitting the bearing socket 2. The nuts 4' serve to draw this journal bolt 4 fast into the bearing socket to prevent inadvertent relative movement. The revolver head 3 is provided with a series (as shown, six) of obliquely extending elongated slots 11, and in its periphery are arranged, intermediate these slots, notches 5 with which operates the snap member or latch bolt 6. The latter, provided with a head 12, is guided within a casing 7 fixed to the support 1, and is acted on by the compression

spring 8 which tends to force the bolt into an alined notch 5. The slots 11 are so disposed in the revolver head relative to the peripheral notches that upon the latch bolt 6 coacting with a notch the respectively oppositely disposed elongated slot extends rectangularly to the latch bolt or support member axis.

For each slot there is provided a stirrup-shaped tool clamp 9, whose laterally extending square shank portion 9' snugly fits the receiving slot across its shorter diameter, so that relative rotary displacement is prevented. The free shank end is threaded as at 9" and a flange nut 13 coacting therewith serves to clamp the tool fast onto the revolver head. In the several figures only one tool and tool clamp are shown, by way of example, to prevent crowding the drawing. The clamp 9 with the tool 10 is moved by hand into the required position until the tool properly faces the work piece and the nut 13 is then tightened up by means of a wrench, when the tool will be securely clamped to the revolver head. Owing to these compound adjusting displacements the tool may be shifted to any desired relative operative position within certain limits.

The practical use of the appliance is the following:—In case a certain work piece has to be operated upon by two or more different tools, these latter, in succession of their order of use, are clamped to the revolver head, the latter with loose nuts 4' and withdrawn latch bolt 6 is turned until the tool to be used first comes opposite the work piece, when the bolt 6 is allowed to snap into the respective notch 5, the nuts 4' are then tightened up, and the work piece is operated on to the required extent. Then, the nuts 4' are eased, the latch bolt 6 is drawn back, the now freed revolver head is rotated until the second tool faces the work piece, the latch bolt is allowed to enter the corresponding peripheral notch 5, and finally the nuts 4' are tightened up again; and so on for each succeeding tool.

A further advantage of the attachment is that also relatively short tools may be used.

What I claim is:

1. In a device of the character set forth, a supporting member adapted to be secured to a lathe or other machine, a tool supporting revolver head having in coacting relation a series of peripheral notches and a cor-

105

110

responding number of elongated slots there-
through, screw and nut means allowing and
preventing rotation of said revolver head
on and relative to said supporting member,
5 latch bolt means coacting with said periph-
eral notches for locking said revolver head
in a plurality of predetermined operative
positions, and a tool clamping member for
each of said elongated slots and adjustably
10 securable therein, substantially as set forth.

2. In a device of the character set forth,
a supporting member terminating in an en-
larged laterally displaced bearing socket
having a tapering bore, a tool carrying head
15 in the shape of a disk with a conical journal
bolt centrally extending therefrom and of
a configuration conforming to the contour
of the tapering socket bore, means for pre-
venting and allowing relative rotation be-

tween said conical bolt and said socket, said
20 tool carrying head having peripheral
notches and elongated slots therethrough,
stirrup-shaped tool clamps adjustably se-
curable in said slots with capability of dis-
placement therein in the longitudinal axis 25
thereof but prevented from relative rotary
displacement, and spring influenced latch
bolt means on the supporting member co-
acting with said peripheral notches in said
tool carrying revolver head for locking the 30
latter in various predetermined operative
positions, said elongated slots being so dis-
posed in the revolver head that the slot re-
ceiving the clamp which binds the operating
tool extends rectangularly to the axis of the 35
said supporting member.

ERNST ORTWIG.
